DRYING MACHINE

Ralph C. Parkes, Glenside, Pa.

Application January 15, 1941, Serial No. 374,448

3 Claims. (Cl. 34—105)

My invention relates to a new and useful drying machine and it relates more particularly to a drying machine which is especially adapted for drying cops, bobbins and the like, provision being made for drying such objects in multiple batteries and also for rapid and simultaneous discharge of the objects, after they are dried, from the machine in large quantities.

Other features of construction and advantage of my novel drying machine will be more clearly understood from the following specification and the accompanying drawings in which:

Fig. 1 represents a diagrammatic top plan view showing the general lay out of the machine with certain parts broken away to show internal details and other parts omitted.

Fig. 2 is likewise a diagrammatic view in front elevation of the machine illustrated in Fig. 1 certain parts being broken away to show internal construction and other parts being entirely omitted.

Fig. 3 represents a view partly in section and partly in elevation taken on line 3—3 of Fig. 2.

Fig. 4 represents, partly in section and partly in elevation, and on an enlarged scale, certain details of construction.

Fig. 5 represents, in front elevation, a fragmentary view illustrating the operation of the parts shown in Fig. 4.

Fig. 6 represents a perspective view of one of the drying units forming part of my drying machine, certain parts being broken away to show details of construction.

Fig. 7 represents a diagrammatic and fragmentary view partly in section and partly in elevation showing a modified form of the construction as shown in Figs. 4 and 5.

Referring to the drawings in which like reference characters indicate like parts, and more particularly to Figs. 1 and 2, my novel drying machine comprises, generally speaking, a relatively big enclosure made of sheet metal or the like and having a suitable reinforced supporting frame, said enclosure being preferably divided into right and left hand sections 8 and 10 and an intermediate section 12. In the intermediate section 12 are mounted the blowers 14 which are provided with reversely disposed blades 16—18 so that they can blow air upwardly through the heaters 20 or downwardly through the heaters 20 as desired. The structure and operation of the reversible fan construction is described fully in prior Patent No. 2,131,691. Conventional suitably controlled inlets for drawing in fresh air and conventional suitably controlled outlets for

exhausting the moist air are provided but the same are not shown in the drawings, which are only fragmentary and diagrammatic, and because they constitute obvious expedients well known to those skilled in the art. While in Figs. 1 and 2 I have shown only one unit of blower assemblies 16—18, it will be understood that in actual practice a plurality of blower units will be used extending transversely through the center compartment 12, the showing of all the blowers having been deliberately omitted in the interests of clarity of illustration. For the purposes of this specification and the claims hereto attached the disclosure must be considered as showing a plurality of blower units extending transversely of the chamber and in line with and below the heating elements 20. The heating elements 20 may be of any desired type and need not be shown or described in detail. The central compartment 12 is provided with the lower and upper baffles 22 and 24 which curve away in opposite directions so as to direct the air blown in either direction through the heaters 20 to the respective end chambers 8 and 10 as shown by the arrows in Fig. 2. The end chambers 8 and 10 are provided with the sloping roofs 26 which serve to deflect and diffuse the air blown into the chambers 8 and 10 in a uniform manner over the entire area of the chambers 8 and 10. Below the sloping roofs 26 are provided the movable slats or baffles 28 which are controlled by levers and which can be adjusted to control the passage of the air into the chambers 8 and 10. Except for forming part of the present combination, the details of construction and operation of the slats 28 form no part of the invention and are therefore not described in further detail, as any conventional form of such slat or baffle may be used.

The drying machine thus far described is provided with a back wall 30 extending the height and length of the machine, end or side walls for enclosing the ends (not shown), a front wall or door for enclosing the central chamber 12 and which may be opened to afford access to the blowers and the heaters contained therein and the fronts of the chambers 8 and 10 are left open except for the upper and lower frames 32 and 34 which extend along the entire front of the machine. The bottom may be enclosed if desired or the machine may be mounted on the floor so that the floor serves as the bottom of the machine. The top of the machine is completely enclosed by a cover or roof 36.

In the compartments 8 and 10 of a drying machine embodying the structure generally de-

scribed, I position a plurality of withdrawable drawers each of which is adapted to support a plurality of cops, bobbins, or the like which are to be dried, said drawers being adapted to be loaded in their withdrawn position and to have their load discharged also in withdrawn position, and to be inserted into the machine to subject the load or charge of cops, bobbins or the like to the drying operation. Since Figs. 1 and 2 are more or less diagrammatic, and since the drawers referred to are identical, I have shown in Figs. 3 and 6 details of one of said drawers and in Figs. 4 and 5 I have shown the mechanism for discharging the load after the material has been dried. Referring now to Figs. 3 and 6 it will be seen that each of the drawers referred to comprises the rear wall 38 which, when the drawer is in position, is adapted to abut against the rear wall 36 of the machine, the front wall 40 provided with a handle 42, and a central guide wall or partition 44. The front and rear walls 38 and 40 of each of the drawers are interconnected near their lower ends by the spaced, parallel angle irons or other framework 46 and are similarly connected at their upper ends by corresponding angle irons or framework 48. The bottom angle irons 46 are adapted to slide against the guides 50 which are carried by spaced, parallel angle irons 52 which are secured to the rear wall 36 and the front, lower frame 34. The angle irons 48 are provided with the plates 54 which carry the brackets 56 which support the rollers 58 which are adapted to travel on the track 60, the track 60 being suitably carried by the cross bars 62 which in turn are suitably secured to the roof or upper framework of the machine. The track 60, as will be best seen from Fig. 6, is preferably of an inverted T-shape and it is adapted to project through a corresponding slot 66 in the front wall 40 of each of the drawers. By the construction thus far described the entire drawer, grasped by the handle 42, can be pulled outwardly from the machine, one of said drawers being shown partly withdrawn at 68 in Fig. 1. To the front wall 40 is preferably suitably secured a pair of brackets 70 which also carry rollers 58 which engage the projecting portion of the track 60 as shown in Fig. 6.

Referring to Figs. 3 and 6 it will be seen that each drawer is provided with a plurality of vertically spaced rods 72 which pass through apertures in the central guide partition 44. Depending on the width of the drawer, two or more rods are positioned in horizontal rows as shown in Fig. 1. The rods 72 may be made integral but are preferably made in two sections interconnected by any suitable connection such as that shown at 76 in Fig. 4 and are urged towards the front and rear walls of the drawer respectively by the springs 78. Each of the rods 72 carries a plurality of vertically standing pins 80 which are adapted to support the cops, bobbins or the like 82 to be dried as partly shown in Figs. 3-4.

With reference to the pins 80, which are shown as supporting the hollow cops or bobbins 82, I wish to point out that the pins 80 can be replaced with hooks from which skeins of yarn can be suspended, or they can be replaced with individual platforms or a continuous platform on which the goods to be dried can be placed, the essence of my invention being that means are provided for supporting a plurality of objects in such a manner that, when the supporting

rods 72 are rotated about their axes as diagrammatically illustrated in Fig. 5, the objects being dried will fall off simultaneously from each of the rods 72. This obviates the necessity of handling the objects themselves while they are hot and also saves considerable time.

Also, it is to be noted that by placing the heating unit 20 and the reversible blower units 14 and 18 in the central compartment 12, which 10 communicates at its top and at its bottom with the end compartments 8 and 10 as shown by the arrows in Fig. 2, I double the capacity of the drying machine without proportionately increasing the capacity of the heating unit or the blowers. Thus, if the heating unit and the blowers were placed at one end of a single compartment equaling in length the combined length of the chambers 8 and 10, the drying medium would be more than is necessary immediately adjacent the heating unit and the blowers but would be less than is enough at the far end of such an elongated drying chamber. By my arrangement and with the provision of the deflecting, curved upper and lower members 24 of the central compartment 12, as well as the sloping roofs 26 of the compartments 8 and 10, I effect adequate diffusion of the hot air so as to get substantial, uniform drying throughout the compartments 8 and 10.

Referring to Fig. 4, and assuming the same to represent an enlargement of the left hand portion of Fig. 3, it will be seen that I have provided on the inner face of the front wall 40 of the drawer a hub or cup-shaped member 84 which is suitably secured in position and which is provided with the aperture 86. The hub 88 is provided with the prongs or other projections 92. In the normal position the spring 78, urging the rod 72 in the direction of the arrow in Fig. 4, causes the pin 90 to engage the aperture 86 with the disc or hub 88 in contact with the inner wall of the cup-shaped member 84. In this position the rod 72 is held rigidly against turning and the cops or the like 82 to be dried are held in the position shown in Fig. 4. After the drying operation is completed, the drawer is withdrawn from the drying chamber and a wrench, such as that shown in Fig. 5 at 94, is engaged with the prongs or projections 92 of the hub 88. Pressure is then applied to disengage the pin 90 from the aperture 86 against the tension of the spring 78 and, since the rod 72 is now free to turn, pressure is applied in the proper direction on the wrench 94 to rotate the rod 72 about its axis so that the pins 80 now point substantially downwardly, whereupon the bobbin or the like 82 being dried drops off by gravity as illustrated in Fig. 5. By inspection of Figs. 3 and 6 it will be seen that the structure disclosed in Fig. 4 and illustrated in operation in Fig. 5 is applied also to the back wall 38 of the drawer so that the corresponding sections of the rods 72, that is, between the back wall 32 and the partition 44, are operated in the same manner as that described in detail for the sections of the rods 72 between the partition 44 and the front wall 40 of the drawer. 96 designates a series of baffle plates which may be of angle or other shapes and which are secured to vertical partitions 98 disposed between each successive pair of drawers, the purpose of the baffle plates 96 being to obstruct the passage of air upwardly or downwardly through the various drawers thus causing the air to eddy and whirl around to retard the passage of air and increase its contact with the goods to be dried. The reverse blower blades 16-18

enable me to direct air upwardly through the heaters 20 and downwardly through the various drawers in the compartments 8 or 10 or, by reversing the direction of rotation of the fan, the heat is drawn downwardly through the heaters 20 and upwardly through the drawers in the compartments 8 and 10. In this way a more thorough drawing of the cops on the pins 80 is effected.

In Fig. 7 I have shown a slightly modified form in which I propose to introduce steam or other heating or drying medium through pipes 100 which take the place of the rods 72, and through the hollow pins 102, which take the place of the solid pins 80 and which support the cops or bobbins 82. The hollow pins 102 are closed or capped as at 104. The hollow pipes 100 pass through the back walls 38 of the drawers and the back wall 39 of the machine and are adapted to slide over the tapered nipple 106 which is connected to the T 108 which in turn forms part of or is suitably connected to the upright manifold 110 which is provided at its lower extremity with the valve 112. Steam, hot air or other drying medium is delivered into the upright manifold 112 from a source not shown, it being understood that the manifold 112 extends upwardly the entire height of the machine and has as many T outlets 108 as there are pipes 100. To the back wall 38 of the drawer is secured a cup-shaped member 114. 116 designates a collar rigidly secured to the pipe 100 so as to be movable therewith. A spring 118 is confined between the collar 116 and the front wall 120 of the member 114. This results in the spring constantly urging the pipe 100 in the direction of the arrow in Fig. 7 so that the rear end of the pipe 100 is constantly engaging the nipple 106. Also keyed or otherwise suitably secured to the pipe 100 is the hub 122 which is provided with one or more pins 124 adapted to engage corresponding openings in the front wall 120 of the member 114. When the pins 124 are in the position shown in Fig. 7, it is obvious that the pipe 100 is retained against rotary movement. In order to be able to rotate the pipe 100 and thus drop off its entire load of cops 82, I have provided the hub 122 with the prongs, lugs or flange 126, which are adapted to be engaged by the wrench 94 of Fig. 5, thus moving the pipe 100 to the right as viewed in Fig. 7, against the tension of the spring 122. This releases the pins 124 from their corresponding openings and the pipe 100 can now be turned about its axis as illustrated in Fig. 5. On the front wall 40 of the drawer there is mounted a sleeve or bearing 128 the length of which is slightly in excess of the range of movement of the pipe 100 so that, when the pipe 100 is in its extreme left hand position, as in Fig. 7, the front end of the pipe 100 still rests within the bearing 128 and so that, when the pipe 100 is moved to the right of Fig. 7, to release the pins 124 and thus turn the pipe 100, the front end of the pipe 100 simply moves inwardly or slides to the right within the bearing 128. The pipes 100, like the rods 72, are preferably supported about the middle thereof by the partition 44.

The operation is as follows:

First referring to that part of the invention shown in Figs. 1 to 6, it will be seen that my invention resides in the provision of the drying chamber which is generally described, and in the building of the batteries of withdrawable drawers each of which in turn carries a plurality of pins each of which supports one or more cops or bobbins or the like to be dried. Beginning with the 75

machine empty, the drawers are pulled out, either successively by one operator or simultaneously by several operators, and, with the pins 80 in their vertical position, the objects to be dried, such as the bobbins 82, are mounted on the pins. The drawers are then pushed back into the machine and into the position best illustrated in Figs. 3 and 6. The fans are operated to deflect the air upwardly so that the air is delivered downwardly through the work in the chambers 8 and 10, or the movement is reversed and the air is fed downwardly so that it is delivered upwardly through the chambers 8 and 10 or both. After the drying operation has been completed, the drawers are pulled out by the handles 42 until the rear wall 38 of each drawer is in line with or just about clears the front frame 32-34 of the machine, whereupon the wrench 94 is applied to the lugs or pins 92 to move the rods 72 against the tension of the spring 78 thus releasing the rods 72 for free rotation about their axes. The wrench is then moved arcuately until the rods 72 are turned to the position shown in Fig. 5, whereupon the bobbins 82 drop off their supporting fins. The rods 72 are then returned to their original position, as shown in Fig. 3 for instance, with the pins 80 pointing upwardly and a fresh charge of cops or bobbins 82 is loaded onto the pins 80 and the drying operation is repeated.

The operation of the form of construction shown in Fig. 7 is as follows:

A drawer having the pipes 100 and hollow pins 102 is withdrawn from the machine in the same 35 manner as above described and the same is loaded with cops, bobbins or the like 82. When this is done the rear end of the pipe 100 is entirely disengaged from the nipple 106 and, of course, while this is done the valve 112 is closed to prevent steam or other heating or drying medium from entering the manifold 110. When the drawer has been loaded it is pushed back into the machine whereupon the ends of each of the pipes 100 slips over the juxtaposed end of the 45 nipple 106 (into the position shown in Fig. 7) and the valve 112 is then opened to permit the drying medium to pass through the manifold 110, the nipple 106, the pipe 100 and the hollow pins 102. In order to insure the automatic and complete engagement of all of the ends of the pipe 100 with their respective nipples 106, it will be seen that I have made the nipples 106 of sufficient length and sufficient taper to facilitate their entry into the juxtaposed ends of the respective pipes 100 regardless of any slight irregularities that may exist in the floor or the framework or that may result from the movement of the relatively large drawers back and forth. If desired, the nipple 106 can be made flexible, such as of hard rubber or the like, so that it may bend if necessary, or it may be provided with a universal joint connection (not shown). After the drying operation has been completed, the valve 112 is closed, the drawer is pulled out of the machine until all the cops or bobbins are outside the front wall of the machine and then the wrench 94 engages the pins or lugs 126 on the hub 122 to push the latter to the right of Fig. 7 against the tension of the spring 118, thus disengaging the pins 124 from the openings in the front wall 120 of the cup-shaped member 114. This permits the pipes 100 to be rotated about their axes so that the cops or bobbins mounted on the hollow pins 102 are dropped off into a basket or onto the floor if desired. The pipes

are then returned into the position shown in Fig. 7 and then a fresh charge of objects to be dried is mounted, the drawers are pushed back into the machine and a new cycle of operation begins.

Having thus described my invention, what I claim as new and desire to secure by Letters Patent is:

1. A drying machine of the character stated comprising a chamber, means for admitting a drying medium into said chamber, a drawer slideable into and out of said chamber, means carried by said drawer for supporting the objects to be dried comprising a rotatably mounted horizontally disposed rod carried by said drawer, a plurality of vertically disposed pins carried by said rod, means for rotating said rod, and means for locking said rod against rotation.

2. A drying machine of the character stated comprising a chamber, means for admitting a drying medium into said chamber, a drawer slideable into and out of said chamber, a hollow horizontally disposed rod carried by said drawer, vertically disposed hollow pins carried by and communicating with the interior of said rod and

adapted to support the object to be dried, and means for introducing a heating medium into said rod and said pins.

3. A drying machine of the character stated comprising a central chamber, a heating element therein, a blowing element cooperating with said heating element, a pair of end chambers communicating with said central chamber, vertical partitions spaced from the top and bottom of said chamber and dividing each of said end chambers into a plurality of compartments each of which communicates at its top and bottom with said central chamber, drawers slideable in and out of each of said compartments, a plurality of rotatably mounted horizontally disposed rods carried by each of said drawers, a plurality of vertically disposed pins carried by each of said rods and adapted to support the material to be dried, means for locking said rods in position, and means for rotating said rods about their axes to dislodge the dried material from said pins.

RALPH C. PARKES.
